CLAIM

The ornamental design for a stair tread, as shown and described.

DESCRIPTION

FIG. 1 is a perspective view of my stair tread; FIG. 2 is an elevational view from the front; FIG. 3 is an elevational view from the rear; FIG. 4 is a left side elevational view; FIG. 5 is a right side elevational view; FIG. 6 is an enlarged left side elevational view of the encircled portion “6” of FIG. 4; FIG. 7 is an enlarged left side elevational view of the encircled portion “7” of FIG. 4; FIG. 8 is a top plan view; and, FIG. 9 is a bottom plan view. The broken lines depict boundaries of the enlargements and form no part of the claimed design.

1 Claim, 6 Drawing Sheets
